[57] **CLAIM**

The ornamental design for an electrooptic timepiece face design, as shown and described.

DESCRIPTION

FIG. 1 is a front elevational view of an electrooptic timepiece face showing our new design in a non-energized condition;

FIG. 2 is a front elevational view thereof in representative energized condition showing a time indication of **10:18**.

The claimed article is flat on front and rear surfaces and is substantially of no appreciable thickness.

FIG.1
